UNITED STATES PATENT OFFICE.

JOHN O. MADISON, OF BROOKLYN, NEW YORK.

SAND-BOX.

1,287,720.

Specification of Letters Patent. Patented Dec. 17, 1918.

Application filed November 30, 1917. Serial No. 204,554.

To all whom it may concern:

Be it known that I, JOHN O. MADISON, a citizen of the United States, residing at Brooklyn, in the county of Kings and State of New York, have invented a certain new and useful Improvement in Sand-Boxes, of which improvement the following is a specification.

This invention relates to sand boxes for use on street cars or other vehicles, and has for its objects to provide improved means for loosening and feeding the sand in the box, and to provide an improved outlet valve of the sliding gate type which shall operate freely and without sticking or clogging with the sand.

One feature of my invention comprises an improved agitating device attached to the sliding gate and actuated by the movement thereof to loosen the sand in the box and assist in feeding the same downward toward the outlet. Another feature comprises an improved construction for loosely mounting the sliding gate in the box whereby ample clearance is afforded around the edges of the gate to prevent binding or sticking of the same due to the clogging of the sand in the groove.

In the accompanying drawing, Figure 1 is a side elevation of my improved sand box as mounted on a car and showing the operative connections extending to the car platform; Fig. 2 a vertical section of the lower portion of the sand box, on a larger scale; and Fig. 3 a similar section taken at right angles to Fig. 2.

As shown in the drawing, the sand box comprises the upper portion or hopper, 5, usually located beneath a car seat and extending down through the floor, and the lower portion or sand trap, 6, attached to the bottom of the hopper and containing the valve for controlling the discharge of sand to the rail. The valve, 7, is of the sliding gate type and may be operated from the car platform by any suitable form of connections, such as pedal, 8, bell-crank lever, 9, and rod, 10, a spring, 11, being employed for returning the gate to closed position.

In the use of sand boxes trouble has been experienced with the sand becoming packed or frozen and not flowing freely from the hopper, and various forms of stirring or agitating devices have been employed for loosening the sand. According to my improvement I employ a bent rod in the form

of a bell-crank, pivotally attached at its lower end to the sliding gate, 7, by means of fulcrum bracket or lugs, 12, and having its lower arm, 13, extending up between fixed guides on the sand trap, and the upper arm, 14, extending in a general transverse direction across the lower portion of the hopper, whereby the movement of the gate, 7, produces a vertical sliding action of the arm, 13, and a vertical swinging movement of the upper arm, 14, for loosening and agitating the sand in the hopper and positively assisting the downward feeding of the same toward the outlet opening past the gate when the same is open. Any suitable form of guiding means may be used for confining and directing the sliding movement of the lower arm of the bell-crank, but I prefer to make the lower arm, 13, curved to engage the side wall of the sand trap on one side during the upward movement and use a rigid fulcrum bar, 15, for the guide on the opposite side to engage the bell crank during the closing movement. The bell-crank is preferably made double with the upper ends joined together as shown.

The fulcrum bracket, 12, rigidly secured to the sliding gate also forms a stop for limiting the opening movement by engaging a side wall of the sand trap.

When the motorman actuates the pedal device for applying sand the sliding gate is drawn to its open position during which movement the arm, 13, of the bell crank is guided vertically against the wall of the trap and extends up into the hopper while the upper arm, 14, swings downward to the position indicated in dotted lines, thereby agitating and loosening the sand in the lower part of the hopper and feeding the same downward toward the outlet past the open gate. During the return or closing movement of the gate the bell crank engages the fulcrum bar, 15, and is returned to its original position, both movements serving to keep the sand in a loose condition.

According to another feature of my improved construction the sliding gate, 7, is loosely mounted in the casing of the box or sand trap being supported on lugs, 16, and just above the gate the walls of the trap are brought inward to form the slopes, 17, the walls overhanging the outer edge of the gate. A groove, 18, is formed in the underside of the overhanging portion of the sloping walls of the trap above and around the

outer edge of the gate for relieving the pressure of sand upon the gate at this point and providing ample clearance for preventing sticking or excessive friction to movement of 5 the gate. By this means the gate is adapted to slide easily at all times and the sand flows freely down the sloping walls and through the outlet of the trap.

What I claim as new and desire to secure 10 by Letters Patent is:

1. A sand box having a sliding gate, and a bent rod forming a bell-crank pivotally attached to said gate and extending upward into said box, the upper end of said rod being actuated downward toward the outlet 15 by the opening movement of the sliding gate.

2. A sand box having a sliding gate, and a bent rod forming a bell-crank pivotally attached to said gate and extending upward into said box, the lower arm of the bell crank having a sliding engagement with a portion of the box and actuating the upper arm of said bell crank downward toward the 25 outlet when the gate is opened.

3. A sand box having a sliding gate, and a bent rod forming a bell-crank pivotally attached to said gate and extending upward into said box, and means for guiding the lower arm of the bell crank by a sliding engagement to actuate the upper arm toward and from the outlet.

4. A sand box having a sliding gate, and

a bent rod forming a bell-crank pivotally attached to said gate and extending upward 35 into said box, the lower arm of the bell-crank having a sliding engagement with the side of the box, upon the opening movement of the gate, and a fulcrum bar for engaging the opposite side of said arm upon the clos- 40 ing movement of the gate.

5. A sand box having a sliding gate, and a bent rod forming a bell-crank pivotally attached to said gate and extending upward 45 into said box, the lower arm of the bell-crank being curved, and fixed guides upon opposite sides of said curved arm for confining and directing its movement.

6. A sand box having a loosely mounted sliding gate, the box being provided with 50 inwardly sloping side walls, overhanging the outer edge of said gate and having a clearance space between the under surface of the overhanging portion of said walls and the top of the gate, and supporting lugs 55 on the opposite side walls beneath the guiding edges of said gate.

7. A sand box having a loosely mounted sliding gate, the box being provided with 60 inwardly sloping side walls overhanging the outer edge of said gate, the overhanging portion of the walls having a groove in its underside and over the outer edge of the gate.

JOHN O. MADISON.
